UNITED STATES PATENT OFFICE.

WILLIAM J. ENGLISH, OF COHOES, NEW YORK.

WATER-TRAP.

SPECIFICATION forming part of Letters Patent No. 293,438, dated February 12, 1884.

Application filed May 9, 1883. (No model.) Patented in Canada November 11, 1883, Nos. 15,777, 16,673, and 16,674.

To all whom it may concern:

Be it known that I, WILLIAM J. ENGLISH, a citizen of the United States, residing at Cohoes, in the county of Albany and State of New York, have invented new and useful Improvements in Water-Traps, of which the following is a specification.

This invention relates to a water-trap of that class which I have described in Letters Patent No. 249,031, granted to me November 1, 1881.

My present invention consists in a water-trap composed of three substantially parallel limbs communicating through two bends, a laterally-projecting enlargement formed in the connecting-limb, and a vent-opening formed on a rectilinear upward continuation of the discharge-limb. My trap is cast of lead, and provided with bell-shaped sockets for the purpose of making the connections with the inlet-pipe and with the waste-pipe.

In the accompanying drawings, Figure 1 represents an elevation, partly in section. Fig. 2 is a vertical section in the plane $\alpha\alpha$, Fig. 1.

Similar letters indicate corresponding parts.

In the drawings, the letter A designates my trap, which is composed of three limbs—viz., the inlet-limb a , the connecting-limb b , and the discharge-limb c . The connecting-limb b is substantially parallel with the limbs a and c , and it communicates with the limb a by a bent, d , and with the limb c by a bent, e . The connecting-limb b is provided with an enlargement or chamber, h , (see Fig. 2,) the object of which is to retain a quantity of air and to prevent the trap from being siphoned out. This chamber also serves as a reservoir containing a large quantity of water, which is not so quickly evaporated as the smaller quantity contained in a limb of ordinary section. The mouth f of the inlet-limb a connects by a pipe, m , with the sink or other device on which the trap is to be used. The discharge-limb c extends upward and forms a vent, i , for gases, being connected with a pipe, l , for discharge in any suitable place. By having the vent i placed as an upward continuation of the discharge-limb, c , instead of placing it on the bent e , as is usually done, I avoid the difficulty which often arises from the vent getting

chocked up with grease. My vent is cast 50 solid with the trap, which is a great saving in labor.

My trap is cast of lead, in two sections, A' A^2 , the section A' being provided with a bell, n , to receive the end of the section A^2 , the connection being made by solder or other suitable means. By referring to the drawings it will be seen that the two sections A' A^2 are united in the middle of the chamber h , and that the mouth f of the inlet-limb a , as well as 60 the vent-opening i of the discharge-limb c , are made in the form of bells, the bell-shaped mouth f being intended to receive the pipe m , which leads to the sewer or other device, as already stated, while the bell-shaped vent-opening i is intended to receive the pipe l , for the discharge of gases.

I am aware that it is not new to construct a water-trap of two parallel limbs connected by an intermediate limb with a vent in the intermediate limb, and therefore lay no claim thereto.

What I claim as new, and desire to secure by Letters Patent, is—

1. A water-trap composed of three substantially parallel limbs, a b c , communicating through two bends, d e , an enlargement formed in the connecting-limb b , and a vent formed by extending the walls of the discharge-limb above the connection with bent e , whereby the 75 vent is located above the discharge-limb and not in the bent e , substantially as described.

2. A water-trap composed of two sections, A' A^2 , the section A' forming the inlet-limb a and part of the connecting-limb b , and being 85 provided at its ends with bells f n , while the section A^2 forms the discharge-limbs c and part of the connecting-limb b , and is provided with a bell, i , substantially as shown and described.

In testimony whereof I have hereunto set my hand and seal in the presence of two subscribing witnesses.

WILLIAM J. ENGLISH. [L.S.]
